UNITED STATES PATENT OFFICE.

JOHN STADNICZEK, OF ELIZABETH, NEW JERSEY.

RAZOR STROP.

Application filed May 20, 1922. Serial No. 562,377.

To all whom it may concern:

Be it known that I, JOHN STADNICZEK, a citizen of Poland, residing at Elizabeth, in the county of Union and State of New Jersey, have invented certain new and useful Improvements in Razor Strops, of which the following is a specification.

The present invention relates to new and useful improvements in razor strops, and 10 has for the primary object thereof the production of a razor strop provided with a novel form of tensioning means, whereby the usual fabric strip and rubber strip are held under a tension desired by the operator 15 for sharpening straight edge razors, safety razors, or other cutting implements.

A further object of this invention is the provision of a razor strop wherein one end of the same may be loosely secured to a 20 hook or the like on a barber's chair or upon the wall of a room, and wherein the usual amount of exertion necessary for applying tension to a razor strop will be dispensed with.

25 With the above general objects in view and others that will appear as the nature of the invention is better understood, the same consists of the novel form, combination and arrangement of parts hereinafter 30 more fully described, shown in the accompanying drawing and claimed.

In the drawing, wherein like reference characters designate corresponding parts throughout the several views,

35 Figure 1 is a side elevational view of my device,

Figure 2 is a front elevational view of one side thereof with one of the strips removed and portions of the invention being shown 40 in cross section,

Figure 3 is a fragmentary enlarged cross sectional view upon the lines III—III of Fig. 2,

Figure 4 is a similar view, but taken upon 45 the broken line IV—IV of Fig. 1, and

Figure 5 is a cross sectional view taken upon the lines V—V of Fig. 3 and looking in the direction of the arrows.

Referring more in detail to the drawing 50 there is shown a razor strop provided with the usual fabric strip 1 and leather strip 2, which strips are rigidly secured at their opposite ends to a frame work hereinafter more fully described. Centrally disposed 55 between the strips 1 and 2 is a longitudinally

arranged bracing member 3, which bracing member is in the form of an oblong strip and may consist of wood or other suitable material. Secured upon the upper end of the member 3 by bolt and nut fasteners 4 60 is a metallic covering 5, the opposite ends of which have longitudinally projecting ears 6 and suitably secured between these ears I have shown a circular wooden block 7. This block 7 need not be of the exact 65 form as shown, but may be square or have any other configuration and for purposes of illustration I have shown this block member 7 secured to the ears 6 by a cross bolt 8. Loosely positioned upon this cross bolt 70 8 and upon the adjacent outer surfaces of the ears 6 is an inverted U-shaped member 9 having a suitable form of hook 10 projecting from the upper edge thereof. The U-shaped member 9 with its complementary 75 hook 10 are adapted to freely swing upon the bolt 8 for allowing the hook member 10 to be engaged upon any desired form of supporting bolt for hanging the razor strop thereto. The adjacent upper ends of 80 the strips 1 and 2 are adapted to overlie each other and are secured to the upper surface of the block 7 by tacks or the like 11.

Upon the bottom edge of the oblong bracing strip 3 is a U-shaped metallic strap 85 member 12 which is so formed as to snugly engage the front and rear faces of the said member 3 and this U-shaped strap 12 is rigidly secured to the mentioned end of the member 3 by bolt and nut connections 13. 90 This strap member 12 is of a width equal to the width of the member 3 and has upon its lower face and intermediate its two ends an enlargement 14, which enlargement has a cylindrical bore 15 passing therethrough in alignment with a relatively long cylindrical bore 16 within the adjacent end of the oblong strip 3. Adapted for passing through the threaded bore 15 of the enlargement 14 in the strap 12 and to be loosely 95 received within the relatively long bore 16 of the strip 3 is a screw threaded cylindrical rod 17. This rod 17 is adjustably held within the bore 16 by a lock nut 18 positioned beneath the enlargement 14 of the strap 12. 105

Beneath the lower end of the oblong strip 3 and the U-shaped metallic strap 12 there is positioned a rectangular metallic plate 19, which plate is mounted for relative movement toward and away from said lower 110

end of the member 3 and the U-shaped strap 12. The opposite sides of the plate member 19 are perforated for the reception of vertically disposed headed bolt members 20, which bolt members are screw-threaded at 22 for permitting locking nuts 23 to be received thereon for permanently mounting the said bolts 20 within the plates 19. The upper ends of these bolts pass through perforations within opposite ends of the bottom face of the U-strap 12 and designated by the numeral 24. Co-extensive with these perforations 24 are inwardly projecting bores 25 within opposite sides of the oblong strip 3, and it will be noted that the perforations 24 in the member 12 and the bores 25 within the member 3 are of a circumference relatively greater than that of the circumference of the bolt 20 whereby free sliding movement of these bolts may be permitted therethrough. Upon the bottom face of the rectangular plate 19 there is centrally arranged a transverse metallic strip 26 which is spaced slightly away from the said plate 25 and is provided with upwardly bent ears 27 for rigidly securing this strip 26 to the said undersurface of the rectangular plate 19 by bolts and nuts 29 and 30 respectively. This strip 26 is provided with a central enlarged opening 31 and positioned within and depending from this opening is an annular shaped thimble 32. The upper end of this thimble 32 is closed by an annular wall 33 which annular wall is of a circumference 35 relatively greater than the circumference of the thimble 32 for effecting a flanged upper end wall. The outer edges of this annular upper wall overlie the inner adjacent edges of the perforation or opening 31 within the strip 26 and this upper wall 33 loosely contacts with the adjacent faces of the rectangular plate 19 and cross strip 26 for allowing a free rotary movement of the sleeve 32. The said upper wall of the thimble has a central screw threaded opening therein, designated by the numeral 34 and coextensive with this opening and centrally of the rectangular plate 19 there is a slightly enlarged opening 35 within this plate. The lower end of the before mentioned screw threaded rod 17 has free passage through the central opening 35 in the plate 19 and the threads of this rod interengage within the threaded opening of the top wall 33 of the thimble 32, and the rod is further received within an elongated bore 37 within a handle member 38. This handle member is of an annular form, and has a reduced upper end portion 39 whereby the same may

be rigidly secured within the depending 60 thimble 32.

The lower ends of the fabric and leather strips 1 and 2, are bifurcated as shown in Fig. 2, whereby spaced fingers are formed thereon and designated by the numeral 40, 65 which bifurcation permits the edges of the strip to pass beyond each side of the handle 38. The ends of these strips overlie each other and are rigidly secured to the bottom of the rectangular plate 19 by headed bolts 70 41 passing through perforations 42 at the four corners of the said plate. The inner ends of these headed bolts are provided with the usual retaining nuts 43.

From the above description it will be 75 clearly seen that tension or stretch may be applied to the flexible strips 1 and 2, by grasping the strop at any desirable point with one hand and by imparting to the handle member 38 a relative turning movement. Any rotation of the handle 38 will effect a rotation of the upper wall 33 of the thimble 32, which upper wall is provided with a screw threaded opening engaging the screw threads of the rod 17. The rod 85 being stationarily mounted within the bore 16 of the strip 13 by the lock nut 18, any turning movement of the aforesaid handle will move the rectangular plate 19 toward or away from the lower end of the said oblong 90 strip. Which movement of the said plate will either increase or decrease the tension of the flexible strips 1 and 2.

Minor changes may be made in the invention without departing from the spirit and 95 scope thereof as claimed.

What is claimed as new is:—

In a device of the class described, a rectangular plate having an opening therein, strap members secured to said plate 100 at one of their ends, an elongated strip having the other ends of said strap members secured thereto, a rotatable thimble in engagement with said rectangular plate, a handle in permanent engagement 105 with said thimble, said elongated strip and the handle being provided with co-extensive bores, and a threaded rod receivable in said bores and having a free passage through said opening in the rectangular plate, said 110 rod being in threaded engagement with said elongated strip and said thimble and being adapted to cause a movement of the rectangular plate toward or away from said elongated strip upon a rotary movement of 115 said handle and thimble.

In testimony whereof I affix my signature.
JOHN STADNICZEK.
